UNITED STATES PATENT OFFICE.

HAROLD MARSH, OF NEW BEDFORD, MASSACHUSETTS, ASSIGNOR TO DRAPER CORPORATION, OF HOPEDALE, MASSACHUSETTS, A CORPORATION OF MAINE.

THREAD-TENSIONING DEVICE FOR AUTOMATICALLY THREADING LOOM SHUTTLES.

Application filed May 28, 1928. Serial No. 281,204.

This invention relates to automatically threading loom shuttles and is more particularly directed to the tensioning means for maintaining the thread under tension 5 during weaving.

It is now the ordinary practice to provide automatically threading loom shuttles with a tensioning device at or adjacent its thread delivery end, to maintain the thread or filling 10 under tension during the weaving operation, and such thread tensioning devices have taken many forms. In weaving with certain kinds or characters of thread or filling, such, for instance, as silk, artificial silk, rayon 15 and the like, much difficulty has been experienced in securing a proper tension to the thread or filling on the first pick of the shuttle following replenishment, and failure of the tensioning means in this respect produces 20 in the cloth what is known as "shiners." This is particularly observable in fabrics formed of silk, artificial silk, rayon, and the like, and one of the principal objects of the present invention is to provide an automatically 25 threading loom shuttle with a tensioning device so constructed and arranged that it will take control of the thread and tension it on the first pick of the shuttle following replenishment, and maintain such tension during 30 the subsequent weaving operations.

An important feature of the present invention consists in a tensioning device for automatically threading loom shuttles comprising two tensioning members having opposed 35 tensioning surfaces curved in a vertical plane transversely of the shuttle in such relation to the path of the swirling thread as it is withdrawn from the shuttle that on the first pick of the shuttle following replenishment the 40 thread will pass at once into control of the tensioning members and have tension applied thereto.

The two tensioning members are normally held in thread tensioning position by yielding means, and one of the tensioning members is formed with a concaved tensioning surface extending heightwise of the shuttle and the other tensioning member is provided 45 with an opposed convexed tensioning surface likewise extending heightwise of the shuttle, the curve of the engaged tensioning surfaces being in substantial correspondence with the path of the swirling thread adjacent the tensioning members as it is withdrawn from the 50 shuttle.

The invention and novel features thereof and new combination of parts will best be made clear from the following description and the accompanying drawings of one good practical form thereof.

In the drawings:

Fig. 1 is a top perspective view of an automatically threading loom shuttle containing the present invention;

Fig. 2 is a detached perspective detail on 65 an enlarged scale of a threading block or shuttle eye showing one of the tensioning members connected to the block and the other disassociated therefrom but in position for application thereto;

Fig. 3 is an end view of the threading block looking from the bobbin chamber and showing the relation of the tensioning members and the relation of the swirling thread to the reversely curved surfaces of the tensioning 70 members;

Fig. 4 is a side elevation of the threading block, looking from the left, Fig. 3; and

Fig. 5 is a side elevation of the threading block containing the present invention and 80 looking from the opposite side of the block, or from the right, Fig. 3.

The present invention is especially applicable to automatically threading loom shuttles wherein the shuttle is partially threaded on 85 the first pick following replenishment and is completely threaded as the shuttle is returned to the replenishing box. The general practice in filling replenishing looms where the filling in the shuttle is changed, is to secure 90 the end portions of the filling in the hopper to a fixed point, so that on the first pick of the shuttle following replenishment the filling will be withdrawn from the shuttle about the end of the bobbin in a swirling path and 95 finally pass into the longitudinal thread passage of the shuttle. The present invention takes advantage of this swirling action of the thread to cause it to pass into control of the tensioning device on the first pick of the 100 shuttle and properly tension the thread, whereby "shiners" or defects in the cloth are obviated.

The shuttle 1, as indicated in Fig. 1, is of the filling replenishing type, and is provided 105 with the bobbin chamber 2 and bobbin holding jaws 3 at one end of the shuttle for engaging the head portion 4 of a filling carrier or bobbin 5. At the delivery end the shuttle is provided with a longitudinally extending 110

thread passage 6 and a side delivery eye 7. In the present instance of the invention, the longitudinally extending thread passage 6 is formed in a threading block which, except as hereininafter more fully described, may be of any general and well-known type.

The threading block 8 has an opening 9 by which the threading block may be held in the delivery end of the shuttle, as usual, through the engagement therewith of the transversely extending holding screw, and, if desired, the threading block may have a downwardly projecting pin 10 to engage a correspondingly shaped recess in the shuttle.

As indicated more clearly in Figs. 2 and 3, the top portion of the threading block 8 has the downwardly inclined portions 11 and 12, one at each side of the entrance to the longitudinal thread passage 6, the purpose being to direct the thread downwardly into and through the longitudinal passage, as usual in filling replenishing shuttles of this general type.

As hereinbefore stated, one of the principal purposes of the present invention is to insure proper tension being applied to the thread on the first pick of the shuttle following replenishment, and to this end the tensioning device is formed of two members having opposed tensioning surfaces extending from a point near the top of the threading block downwardly in a curved path corresponding substantially to the path of the swirling thread as it is withdrawn from the shuttle and passes about the end portion 13 of the filling carrier or bobbin. In the present illustration of the invention, the tensioning device is formed of a fixed and a movable tensioning member, and such construction is a good practical form of the present invention, although it may be modified in this respect, the essential being that the reversely curved tensioning surfaces of the tensioning members shall extend downwardly in a curved path such that as the swirling thread is withdrawn from the end of the bobbin, it will take a natural course into and between the tensioning members.

In accordance with the form of the invention shown, one of the tensioning members, as 14, is held in fixed position at the entrance to the longitudinally extending thread passage, and has its upper portion 15 flared outwardly and secured in fixed position to the threading block so that it presents no obstruction to the passage of the thread. The fixed tensioning member 14 has the concaved downwardly extending tensioning surface 16 which is preferably continued downwardly beyond the entrance to the thread passage. As herein shown, the fixed tensioning member has an outwardly extending projection 17 between the top and bottom thereof which may be secured to a portion 18 of the threading block in appropriate manner, as by sol-

dering or brazing, or otherwise. It is desirable that the downwardly concaved tensioning surface shall extend as far as the bottom of the longitudinally extending thread passage, but in the present instance it is carried beyond, as indicated at 19, so that all danger of the thread catching at the entrance to the thread passage is avoided.

Opposed to the fixed tensioning member 14 is the movable tensioning member 20 having a convex downwardly extending thread tensioning surface which conforms to the concave tensioning surface of the fixed tensioning member, so that the two tensioning members have opposed reversely curved tensioning surfaces which extend downwardly from near the top of the threading block in a curve corresponding substantially to the path of the thread adjacent the entrance to the thread passage 6, as it swirls about the end of the filling carrier or bobbin while the thread is being withdrawn from the shuttle.

In the present instance of the invention, the movable tensioning member 20 has an upper interlocking portion 21 adapted to engage a shouldered recess 22 in the threading block, as shown, Fig. 2, the construction being such that the movable tensioning member may articulate or swing about its connection with the threading block and in a direction toward the fixed tensioning member 14, and when in thread tensioning relation with the fixed tensioning member is locked from disengagement with the threading block.

In the present instance of the invention, the locking portion 21 of the movable tensioning member has a recess 23 which engages about the shoulder 22* of the recess 22, and a tongue portion 24 which engages the inner portion of the shouldered recess 22 formed in the threading block, as indicated more clearly in Fig. 5, with the result that while the tensioning member may be connected to the threading block by swinging it upwardly, as indicated in Fig. 2, and then moving it laterally and downwardly, the tongue 24 will thereafter retain the movable tensioning member in its assembled relation with the threading block, with permissive movement of the tensioning member 20 toward the fixed tensioning member. This particular means of connection between the movable tensioning member and the threading block may obviously be varied, but the construction described represents a good practical form of connecting the movable tensioning member in opposed relation with the fixed tensioning member at the entrance to the longitudinally extending thread passage 6, so that the swirling thread will be caused to engage the tensioning members between the end 13 of the filling carrier or bobbin and the entrance to the longitudinal thread passage.

The tensioning effect on the thread between the tensioning members is caused by resilient

means normally acting upon the movable tensioning member 20 to cause the two reversely curved tensioning surfaces to be pressed toward each other into substantial contact. As 5 one good form of means for maintaining the relation between the tensioning members, the movable tensioning member 20 is extended downwardly beyond the longitudinal thread passage 6, as indicated at 25, and is there connected with a resilient or elastic strip or strap 26 the end 27 of which may be suitably knotted at the outside of an opening formed in the lower end 25 of the tensioning member. The elastic band 26 is then carried laterally through a recess 28 formed in the lower portion of the threading block and its upwardly extending portion 29 is then stretched and passed into an opening 30 formed between the lugs 31 projecting from the top portion 12 of the threading block, the result being that upon the release of the stretched elastic member 26, its upper end portion 32 will expand and consequently retain the elastic member under tension in drawing upon 20 the movable tensioning member 20 to maintain the reversely curved tensioning surfaces in thread tensioning relation. The elastic member or band 26 forms a good practical construction for acting upon the movable tensioning member 20, but in the broader aspects 25 of the invention, other means, of course, might be employed for this same purpose.

When the shuttle is picked following replenishment, the thread *a* will take a swirling course about the end of the filling carrier or bobbin 13 which is indicated in Fig. 3, and as the shuttle moves from the replenishing box to the opposite side of the loom, the swirling thread *a* will engage one or the other 35 of the downwardly inclined portions 11 or 12 of the threading block and be guided into the entrance between the outwardly flaring upper end portions 15 and 33 of the two tensioning members. As the shuttle proceeds on 40 its course, the thread *a* will pass around the end 13 of the filling carrier or bobbin, as indicated in Fig. 3, in the direction of the arrow, and will be given a downward pull as it passes from the top to the lower portion of 45 the end 13 of the filling carrier or bobbin, as represented successively by the lines *b*, *c*, *d*, *e* and *f*, with the result that during the first flight of the shuttle following replenishment, the thread *a* during its swirling action about 50 the end of the bobbin, will travel a path substantially coincident with the curved tensioning surfaces of the fixed and movable tensioning members, and, finally, before the shuttle has reached the opposite box, will pass 55 between the curved surfaces of the tensioning members and be given the desired tension. On the return movement of the shuttle to the replenishing box, the thread will obviously 60 remain between the tensioning surfaces as it passes to the side delivery eye of the shuttle, so

that on the first pick of the shuttle following replenishment, the same tension is placed upon the thread as maintains during subsequent weaving, thereby eliminating "shiners" or defects in the cloth.

From the construction described it will be obvious that the present invention provides opposed tensioning members at the entrance to the thread passage and having curved tensioning surfaces extending heightwise of the shuttle in substantial correspondence to the path of the swirling thread at the part thereof adjacent the entrance to the longitudinal thread passage. The effect of this is that the swirling thread takes a natural course as it 70 is withdrawn from the bobbin and is engaged between the two curved tensioning surfaces during the first flight of the shuttle following replenishment, and while the details of the construction hereinbefore described embody a 75 good practical form thereof, it is evident that such construction may be varied within the true scope of the present invention, one of the essentials of which is that the opposed tensioning members shall present curved tensioning 80 surfaces extending heightwise of the shuttle adjacent the entrance to the longitudinally extending thread passage between which the thread will naturally pass as it swings about the end of the bobbin, so that on the first pick 85 of the shuttle following replenishment the thread will be given the same service tension as it will have during subsequent weaving.

What is claimed is:

1. A tension device for automatically 100 threading loom shuttles, comprising tensioning members having opposed friction surfaces extending heightwise of the shuttle in a curve substantially corresponding to the swirling path of the filling as it is withdrawn from the 105 shuttle that the filling may be engaged between the curved friction surfaces and tensioned on the first pick following replenishment.

2. A tension device for automatically 110 threading loom shuttles, comprising tensioning members having opposed friction surfaces extending heightwise of the shuttle in a curve substantially corresponding to the swirling path of the filling as it is withdrawn from 115 the shuttle that the filling may be engaged between the curved friction surfaces and tensioned on the first pick following replenishment, and means tending to force the curved friction surfaces towards each other.

3. An automatically threading loom shuttle having a longitudinal thread passage and side delivery eye, a tension device formed of two members having friction surfaces between which the thread is tensioned and which cross 125 the longitudinal thread passage in a curve substantially corresponding to the path of the swirling thread as it is withdrawn from the shuttle.

4. A tension device for automatically 130

threading loom shuttles, comprising, in combination, two members, one of which has a concaved tensioning surface and the other an opposed convex tensioning surface, both extending from the top portion towards the bottom of the shuttle in a curve substantially corresponding to the curve of the swirling thread as it is withdrawn from the shuttle, and means for yieldingly pressing the curved tensioning surfaces relatively into thread tensioning position to impart tension to the thread on the first pick of the shuttle following replenishment.

5. A tension device for automatically threading loom shuttles, comprising, in combination, two members having outwardly flaring upper portions and one of which has a concaved tensioning surface and the other an opposed convex tensioning surface, both extending from the top portion towards the bottom of the shuttle in a curve substantially corresponding to the curve of the swirling thread as it is withdrawn from the shuttle, and means for yieldingly pressing the curved tensioning surfaces relatively into thread tensioning position to impart tension to the thread on the first pick of the shuttle following replenishment.

6. An automatically threading loom shuttle having a bobbin chamber, a side delivery eye, and a longitudinally extending thread passage, a thread tensioning device at the entrance to the thread passage comprising two members having thread engaging tensioning surfaces reversely curved in a vertical plane extending transversely of the shuttle that the swirling thread may be engaged between the tensioning surfaces and tensioned thereby on the first pick of the shuttle following replenishment, and yielding means normally acting to press the reversely curved surfaces into thread tensioning relation.

7. An automatically threading loom shuttle having a bobbin chamber, a side delivery eye, and a longitudinally extending thread passage, a thread tensioning device at the entrance to the thread passage comprising two members having thread engaging tensioning surfaces reversely curved in a vertical plane extending transversely of the shuttle that the thread may be engaged between the tensioning surfaces and tensioned thereby on the first pick of the shuttle following replenishment, and an elastic band acting to draw the curved tension surfaces into thread tensioning relation.

8. An automatically threading loom shuttle having a bobbin chamber and side delivery eye, a threading block having a longitudinal thread passage, a fixed tensioning member secured to the threading block at one side of the entrance to the thread passage, an opposed tensioning member mounted on the threading block at the opposite side of the

thread passage for movement toward the fixed tensioning member, one of said tensioning members having a thread tensioning surface concavely curved from top to bottom and the other tensioning member having a convexly curved tensioning surface conforming to the concavely curved surface of the companion tensioning member, and means acting yieldingly on the movable tensioning member to maintain the reversely curved tensioning surfaces in thread tensioning relation.

9. In an automatically threading loom shuttle, the combination of a threading block having a longitudinal thread passage, fixed and movable tensioning members having thread tensioning surfaces curved to correspond substantially to the path of the swirling thread and between which the thread is tensioned on the first pick of the shuttle following replenishment, and a yielding pull device acting to hold the tensioning surfaces in thread tensioning relation.

10. In an automatically threading loom shuttle, the combination of a threading block having a longitudinal thread passage, fixed and movable tensioning members having thread tensioning surfaces curved to correspond substantially to the path of the swirling thread and between which the thread is tensioned on the first pick of the shuttle following replenishment, and an elastic band acting on the movable tensioning member below the thread passage to maintain the tensioning surfaces in thread tensioning position.

11. In an automatically threading loom shuttle, the combination of a threading block having a longitudinal thread passage, fixed and movable tensioning members provided with outward flaring upper end portions having thread tensioning surfaces curved to correspond substantially to the path of the swirling thread and between which the thread is tensioned on the first pick of the shuttle following replenishment, and a yielding pull device acting to hold the tensioning surfaces in thread tensioning relation.

12. In an automatically threading loom shuttle, the combination of a threading block having a longitudinal thread passage, thread tensioning members having tensioning surfaces arranged in a vertical curve corresponding to the path of the swirling thread as it is withdrawn from the shuttle, one of said tensioning members being mounted for swinging movement toward the opposite tensioning member that the swirling thread may, by its normal swirling movement, enter between the tensioning surfaces and be tensioned on the first pick of the shuttle following replenishment.

13. In an automatically threading loom shuttle, the combination of a threading block having a longitudinal thread passage, thread tensioning members having tensioning sur-

faces arranged in a vertical curve corresponding to the path of the swirling thread as it is withdrawn from the shuttle, one of said tensioning members being mounted for swinging movement toward the opposite tensioning member that the swirling thread may, by its normal swirling movement, enter between the tensioning surfaces and be tensioned on the first pick of the shuttle following replenishment, and an elastic band secured to the swinging tensioning member and held under lengthwise stretch.

14. A tension device for automatically threading loom shuttles comprising opposed tensioning members having friction surfaces between which the thread is tensioned, and

an elastic band secured to the movable tensioning member and held under lengthwise tension.

15. A tension device for automatically 20 threading loom shuttles, comprising tensioning members having reversely curved tensioning surfaces in a vertical plane transversely of the shuttle to engage and tension the thread on the first pick of the shuttle following re- 25 replenishment, and means acting yieldingly to force the tensioning members into thread tensioning relation.

In testimony whereof, I have signed my name to this specification.

HAROLD MARSH.
